Primary Examiner — Cynthia Underwood*(74) Attorney, Agent, or Firm* — Fay Sharpe LLP(57) **CLAIM**

The ornamental design for a cable hook, as shown and described.

DESCRIPTION

FIG. 1 is a top perspective view of a cable hook showing our new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a bottom plan view thereof;

FIG. 7 is a top plan view thereof; and,

FIG. 8 is a bottom perspective view thereof from a second direction.

The parts shown in broken lines in FIGS. 1-4 and 6-8 form no part of the claimed design.

1 Claim, 8 Drawing Sheets(56)
